UNITED STATES PATENT OFFICE.

HERBERT BAWDEN AND WILLIAM HOSKIN, OF CENTRAL CITY, COLORADO,
ASSIGNORS OF ONE-THIRD TO HERBERT C. EASTMAN.

SAFETY MECHANISM FOR ELEVATORS.

No. 846,386.

Specification of Letters Patent.

Patented March 5, 1907.

Application filed October 14, 1905. Serial No. 282,805.

To all whom it may concern:

Be it known that we, HERBERT BAWDEN and WILLIAM HOSKIN, citizens of the United States, residing at Central City, in the county of Gilpin and State of Colorado, have invented certain new and useful Improvements in Safety Mechanisms for Elevators; and we do hereby declare the following to be a full, clear, and exact description of the invention, such as will enable others skilled in the art to which it appertains to make and use the same.

This invention relates to improvements in elevators, and more particularly to a safety mechanism therefor.

The object of the invention is the provision of means for facilitating the stopping of an elevator in the event of the same descending accidentally.

With this and other objects in view the invention consists of certain other novel constructions, combinations, and arrangements of parts, as will be hereinafter fully described, illustrated in the accompanying drawings, and more particularly pointed out in the claims hereto appended.

In the drawings, Figure 1 is a view in side elevation of a mechanism constructed in accordance with the present invention. Fig. 2 is a front view in elevation of the mechanism depicted in Fig. 1. Fig. 3 is a top plan view of the mechanism. Fig. 4 is an inverted plan view of the mechanism, showing the bottom of the structure. Fig. 5 is an enlarged view, in side elevation, of one of the key-plates. Fig. 6 is a view in side elevation of one of the slidable locking or catch members. Fig. 7 is a perspective view of the bowed projecting side plate, key-plate, and dog, with portion broken away to exhibit the structure.

Referring to the drawings, 1 designates the platform of the cage, which is secured to the vertical beams 2 2, preferably I-beams. The I-beams 2, Fig. 3, are each provided with two sets of parallel flanges 3 and 4, respectively. Secured near the upper end of the vertical beams of the cage is a horizontal beam 5. The vertical guides of an ordinary elevator - well are positioned between the parallel flanges 4 4 of the I-beams 2. Brace- rods 5' are secured to each end of the plat- form and to the vertical I-beams. Horizon-

tal brace-rods 6 are secured near each of their ends to the brace-rods 5' and engage the I-beams.

Slidable rods or members 7 are positioned between the flanges 3 3 of the upright beams 2 of the cage. Fixedly secured by any suitable means to the upper end of the slidable rod 7 is a draw-head 8. The draw-head 8 is preferably upwardly bowed intermediate its ends. A draw-head bolt 9 is slidably supported upon the cage-beam 5 and is connected centrally to the draw-head 8. The draw-head bolt 9 is provided with an aperture 10, Fig. 1. The apertured structure of the draw-head permits an ordinary lifting-cable (not shown) to be secured to the draw-head bolt. Vertical posts 11 are secured at their lower ends to the draw-head 8 and extend through apertures formed in the cage-beam 5. These bolts are capable of slidable movement within the cage-beam 5. Surrounding each of the posts 11 is yielding means—as, for instance, spring 12. These springs 12 normally exert downward pressure upon the draw-head, which pressure is overcome by the weight of the elevator, being normally suspended upon the draw-head bolt 9. In the event of the lifting-cable being broken accidentally the springs 12 will instantaneously force the draw-head 8 and the rod 7 7 downward for actuating the safety devices.

Secured upon opposite sides of the elevator-cage are projecting-plates 13, which are bent at 14, Fig. 4, for spacing the main portions from the sides of the cage. The ends of each of the plates 13 are secured to the platform of the cage by any suitable fastening means. Secured to the lower end of each of the slidable rods 7 is a key-plate 15, Fig. 5, which performs the function of a cam for adjusting the locking devices. Each of the key-plates 15 is provided with elongated apertures 16 and with a vertical apertured extension 17. It will be noted that these key-plates are of wedge-shaped structure. Each of the protecting-plates 13 is provided with an elongated slot 18, which extends longitudinally of the protecting-plate. Positioned below the platform or floor 1 and also below the parallel beams 19 of the cage are parallel movable shafts or rods 20. These shafts extend through the elongated

apertured portions 18 of the protecting-plates 13. The key-plates 15 are positioned between the sides of the cage and the protecting-plates 13, Fig. 4. The shafts 20 not only project through the elongated apertures 18 of the protecting-plates, but also through the registering elongated apertures 16 of the key-plates, so that when the key-plates are vertically adjusted the shafts 20 will be moved longitudinally within the slots 18 of the protecting-plates. Projecting outwardly from each of the protecting-plates 13 is preferably a pair of shafts 21. Upon each of these shafts 21 there is mounted a dog or pawl 22. A washer 21' is carried by each of the shafts or pins 21, between which and the protecting-plate 13 said dog or pawl is secured. Each of the shafts 20 extends through the upper portion of two of the dogs 22. Horizontal movement of the shafts 20 will cause the dogs 22 to be swung upon the shafts or pins 21. Upon one side of the elevator each shaft 20 extends through a key-plate 15, a protecting-plate 13, and a pawl or dog 22. Vertical movement of the key-plates will cause the shafts 20 to be moved laterally and will consequently actuate the dogs or pawls from removing the same from engagement with the ordinary elevator-guides between which the cage or carriage slides.

Slidable catches are carried by the cage which are adapted to be projected beyond the sides for engaging a suitable stop—as, for instance, a floor—when the carriage is accidentally descending. Each of these slid- 35 able catches comprises a flat plate 23, which is provided with an auxiliary metallic reinforcing-plate 24. Preferably a pair of apertured ears 25 are mounted upon each of the shafts 20 between the parallel beams 19. Each of the ears 25 is provided with a tapering horizontal extension which engages the bottom of a plate 23. These ears 25 and 40 plates 23 are fixedly connected by any suitable fastening means—as, for instance, bolts or rivets 26. The plates 23 and 24 are bifurcated, Figs. 3 and 4, producing extensions 27, which are capable of being projected beyond the ends of the carriage or cage for engaging a floor as the elevator descends in the well. Blocks 28 are positioned beneath the platform 1 and are fixedly secured by any suitable means—as, for instance, rivets 29. 45 These blocks limit the movement of the slid- 50 able plates which constitute the longitudinally-movable catch devices. A transverse beam 30 is secured between the parallel longitudinal beams 19 below the platform 1. Bowed springs 31 are secured centrally 60 to the transverse beam 30. The outer ends of each of said springs engage the inner end of a plate 23. These springs 31 not only force the slidable catches outward, but by 65 reason of the connections between the plates

23 and the dogs or pawls 22 said dogs or pawls will also be swung upon their pivot for causing the same to synchronously engage the guides when the longitudinal movable catches are projected for engaging stops—as, 70 for instance, a floor. Downward projections 32 are formed upon a plate 33, which is secured to the bottom of each of the beams 19. Between these parallel extensions or projections 32 parallel movable shafts or rods 20 75 are positioned. These projections 32 limit the lateral movement of the shafts 20.

When the draw-head 8 moves downward, the key-plates 15, owing to the diverging elongated slots formed therein, will cause the 80 horizontal shafts 20 to be moved apart, thereby sliding the outer end of the plates 23, which is provided with the extensions 27, beyond the side of the carriage or cage and also cause the pawls or dogs to engage the 85 vertical guides between which the elevator slides.

What we claim is—

1. The combination with an elevator-car, of a draw-head carried by said car, a post fixedly secured at one end to said draw-head and extending through a portion of said car, a spring surrounding said post, rods fixedly secured to said draw-head, key-plates fixedly secured to said rods, each key-plate provided with diverging elongated apertures, movable, horizontal shafts positioned within the apertured portions of said key-plates, and pivoted dogs carried by said car and engaging and coöperating with said shafts. 90

2. The combination with an elevator-car, of outwardly-bowed protecting-plates carried by said car, a movable shaft carried by said car and supported upon said protecting-plates, dogs carried by said car and engaging and coöperating with said shaft, and means positioned between said protecting-plates and car and being capable of moving said shaft laterally for actuating said dogs. 105

3. The combination with an elevator-car, of spaced plates carried rigidly by the car and provided each with a horizontal slot, plates movably mounted adjacent the rigid plates and provided with inclined slots, shafts extending through the horizontal and inclined 110 slots, pawls carried by the shafts and pivoted upon the rigid plates, and means to move the movable plates. 115

4. The combination with an elevator-car, of spaced plates carried rigidly by the car and provided each with a horizontal slot, plates movably mounted adjacent the rigid plates and provided with slots reversely inclined from the vertical, shafts extending through the horizontal and inclined slots, pawls carried by the shafts and pivoted upon the rigid plates, and means to move the movable plates. 120

5. The combination with an elevator-car, of spaced plates carried rigidly by and at op- 130

posite sides of the car, and provided each with a horizontal slot, plates movably mounted adjacent the rigid plates and provided with inclined slots registering with the horizontal slots, shafts extending through the horizontal and inclined slots, pawls carried by the shaft and pivoted upon the rigid plates, and means to move the movable plates.

10 6. The combination with an elevator-car, of spaced plates carried rigidly by and at opposite sides of the car, and provided each with a horizontal slot, plates mounted adjacent the rigid plates and provided with inclined slots registering with the horizontal slots, shafts disposed transversely of the car and extending through the registering horizontal and inclined slots, pawls carried by the shafts and pivoted upon the rigid plates, 15 and means to move the movable plates.

7. The combination with an elevator-car, of spaced plates carried rigidly by and at opposite sides of the car and provided each with a horizontal guide-slot, plates movably 20 mounted adjacent the rigid plates and provided with guide-slots reversely inclined from the vertical and registering with the horizontal guide-slots, shafts disposed transversely of the car and extending through the 25 horizontal and inclined slots, pawls carried 30 upon the extended ends of the shafts and

pivoted upon the rigid plates, and means to move the movable plates vertically.

8. The combination of an elevator-car, a protecting-plate carried by the car and spaced therefrom, a slidably-mounted key-plate interposed between the car and the protecting-plate, a shaft movably mounted on the car and protecting-plate and loosely connected to the key-plate, a catch having 40 operative connection with the shaft, and means for actuating the key-plate to control the catch.

9. The combination of an elevator-car, a protecting-plate carried by the car and spaced therefrom, a slidably-mounted key-plate interposed between the car and the protecting-plate, the said key-plate being formed with an elongated opening, a shaft passing through the elongated opening in the key-plate and movably mounted upon the car and protecting-plate, a catch having an operative connection with the shaft, and means for actuating the key-plate to control the catch.

In testimony whereof we affix our signatures in presence of two witnesses.
